ARTHUR BRIGHT BARNES, OF NEW YORK, N. Y., ASSIGNEE TO BARNES ELECTRIC MANUFACTURING COMPANY, OF NEW YORK, N. Y., A CORPORATION OF NEW YORK.

LAMP FIXTURE AND SOCKET CONSTRUCTION.

Application filed February 16, 1922. Serial No. 537,059.

To all whom it may concern:

Be it known that I, ARTHUR B. BARNES, a citizen of the United States, and a resident of the city of New York, borough of Manhattan, in the county and State of New York, have invented a new and Improved Lamp Fixture and Socket Construction, of which the following is a full, clear, and exact description.

10 This invention relates to a construction of lamp fixture and socket, and has for an object the provision of means whereby the socket is in a simple and efficient manner connected to and clamped within the fixture.

15 Another object resides in the provision of means whereby the means for operating the switch in the socket depends from the fixture in an entirely new and convenient manner.

20 A further object resides in the provision of means whereby the support for the socket within the fixture and the device for clamping the parts of the fixture together are utilized as a passageway for the switch operating means whereby said means depends from the fixture in an entirely novel manner.

25 A still further object resides in the particular construction and arrangement parts which are hereinafter described and claimed 30 and shown in the accompanying drawings.

The invention is illustrated in the drawings, of which—

Figure 1 is a side view of the device and is attached to a suitable support, such as a 35 bed, showing the fixture partly in section.

Fig. 2 is a partial sectional view of the fixture showing the socket therewithin taken in a plane at right angles to the section taken in Fig. 1.

40 The form of the invention shown in the drawings is a preferred form, although it is understood that modifications in the construction and arrangement of the parts and in the character of the materials used may be adopted without departing from the spirit 45 of the invention.

The invention in general relates to a fixture which is made in two pieces, such as a 50 cup 1 and a cap 2 within which a socket 3 is to be disposed. This socket as shown is preferably of the pull chain type and has the usual 55 pull chain 4 extending therefrom. The fixture is supported by an arm 5 from a wall plate or bracket member 6. This may be at-

tached to a wall or other suitable support. 55 This bracket or plate 6 is shown provided with a curved clamping plate 7 which adapts the device to be supported or applied to the head frame of a bed or any similar point of support. The circuit wires are contained in 60 a cable 8 which is let in at 9 to the arm 5 and connected in the usual manner to the socket 3.

The socket 3, the upper end 10 of which is shown in Fig. 1, extends slightly beyond the opening in the cover 2 and is fastened in 65 the opening of the cover 2 by any suitable means, such as cement, so that the socket and the cover are movable as one unit. The cap 2 is provided with depending annular ring portions 11 which fit over the corresponding portion 12 on the cup 1. The bottom of the socket is in the usual manner formed with a screw-threaded bore, and in the construction shown is fitted with a threaded hollow pipe 13. This pipe extends 70 downwardly from the end of the socket and is, of course, in line with the axis of the socket. This pipe is adapted to pass through an opening such as 14 in the bottom of the cup 1. It may be threaded through such 75 opening or may pass loosely therethrough.

The lower end of the pipe 13 is to be received in a threaded bore 15 of a nipple 16. This nipple is provided with a smaller bore 17 extending therethrough in line with the 80 bore of the pipe 13. By threading the nipple 16 on to the pipe 13, it will be observed that the cap 2 will be more tightly held on the cup 1 and, consequently, the socket will be more firmly mounted within the fixture. 85 The pull chain 4 is passed through a lateral opening such as 18 in the pipe 13 and thence downward through the pipe and the bore 17 to the nipple 16. The pull chain, therefore, extends downwardly from the bore in the 90 nipple and this causes it to depend from the fixture centrally from its lowest point. This dependence of the pull chain permits its operation so that the pull on the chain is substantially coincident with the axis of the 95 socket and, therefore, no lateral strains are placed thereon. Moreover, the dependence of the chain from the central lower point of the fixture gives a very pleasing, neat, 100 symmetrical effect as contrasted with its dependence from some point on the side of the fixture, as is usually the case.

It will, therefore, be seen that I have pro-

vided a simple and efficient construction whereby the parts of a fixture can be readily disassembled for repair or replacement and yet be simply and firmly held together when 5 in use. I also provide means whereby the switch actuating member, such as a pull chain, in extending or depending from the fixture will not mar its symmetrical appearance and in this way the pleasing effect 10 of the fixture is enhanced while still permitting the ready operation of the switch in the usual manner.

What I claim is:

1. An electric light pull-chain socket construction which comprises a tubular member fastened to the lower end of the socket, said member having a lateral opening to receive a pull chain associated with the socket whereby the pull chain can extend from the 20 lower end of the tubular member substantially in line with the axis of the socket.
2. A lamp fixture construction having a pull chain socket within the fixture, which comprises a threaded tubular member connected to the lower end of the socket, said member having a lateral opening therein within the fixture, the lower end of the member extending through the bottom of the fixture, a hollow nipple on the outside 30 of the fixture engaging with the lower end of the tubular member to support the socket within the fixture, the pull chain of the socket extending through the lateral opening and down through the nipple whereby it 35 depends centrally from the lower face of the

fixture and substantially in line with the axis of the socket.

3. A lamp fixture construction involving a pull chain socket within the fixture, which comprises a cap for the fixture to which the 40 socket is fastened, a tubular member connected to the lower end of the socket and extending through the bottom of the fixture, and means disposed against the bottom of the fixture on the outside thereof to engage 45 with the tubular member, said means being adjustable to hold the socket in position within the fixture and the cap tightly on the body portion of the fixture.

4. A lamp fixture construction involving 50 the use of a pull chain socket within the fixture, which comprises a cap, a body portion on which said cap is to be disposed, the socket being fastened to the cap portion, a threaded tubular member connected to the lower end of the socket and having a lateral 55 opening therein within the fixture, a hollow nipple on the outside of the fixture and engaging with the lower end of the tubular member which extends through the bottom 60 of the fixture, said nipple being adjustable to tighten the cap on the body portion whereby the cap and socket are held rigidly in place, the lateral opening in the tubular member receiving the pull chain which extends through the hollow nipple and depends from the fixture substantially in line 65 with the axis.

ARTHUR BRIGHT BARNES.
